CHILD'S MARBLE GAME APPARATUS

Raymond C. Gaston, Madeira, Ohio, assignor to The Chas. Wm. Doeple Manufacturing Company, Inc., Rossmyne, Ohio, a corporation of Ohio

Application June 13, 1957, Serial No. 46,588

Term of patent 14 years

(Cl. D34—15)

The opposite side not shown is substantially a mirror image of the side shown in Fig. 3.

The drawing figures are diagonally lined to indicate transparency.

The broken line showing of marbles is for illustrative purposes only.

I claim:

The ornamental design for a child's marble game apparatus, substantially as shown and described.
